UNITED STATES PATENT OFFICE.

MARION L. SHACKLEFORD, OF OATMAN, ARIZONA.

FLYING-MACHINE.

1,028,971.

Specification of Letters Patent. Patented June 11, 1912.

Application filed December 24, 1910. Serial No. 599,228.

To all whom it may concern:

Be it known that I, MARION L. SHACKLEFORD, a citizen of the United States, residing at Oatman, in the county of Mohave and State of Arizona, have invented certain new and useful Improvements in Flying-Machines, of which the following is a specification.

My invention relates to a flying machine, embodying the principles of an aeroplane and balloon combined.

My machine is easy to control during flight, traveling readily with and against currents of air, and turning from its course of travel and rising or descending at the instigation of the operator.

An important object of this invention is to provide a flying machine which is capable of fulfilling its function proficiently, without subjecting the operator to the dangers generally encountered in the type of machines known as "heavier-than-air flying machines."

Other objects and advantages of this invention will be apparent during the course of the following description.

In the accompanying drawings forming a part of this specification, and in which like numerals are employed to designate like parts throughout the same,

Figure 1 is a side view of my flying machine, Fig. 2 is a forward end view, Fig. 3 is an enlarged detail sectional view taken through the side plane or wing, Fig. 4 is a plan view of the machine, with the gas bag removed, and Fig. 5 is an enlarged detailed view of the means for securing the side wings to the body structure.

In the drawings, wherein is illustrated a preferred embodiment of my invention, the numeral 1 designates a body-plane, which is a gliding structure. This body-plane comprises a suitable frame 2, carrying two layers of canvas or other suitable material 3, whereby the same may be inflated with gas. It will be seen that this body-plane may be rendered lighter than or substantially equal in weight to the atmosphere. Disposed above and adjacent the body-plane 1, is a gas-bag 4, which is secured to the body-plane by means of suitable cables 5. This gas-bag may preferably have the elongated cylindrical shape, as shown, both ends thereof tapering to points which lie adjacent the body-plane.

The travel of the flying machine in a hori-

zontal plane, is controlled by forward and rear vertical rudders 6 and 7. The forward rudder is disposed below the body-plane 1, and is suitably pivotally connected to the forward pointed end of the frame-work 2 of said body-plane 1, as shown. As clearly illustrated in Fig. 4, a guide bracket 8 is suitably connected by means of pin 9 with the frame-work of the body-plane 1. The transverse portion 10 of this guide bracket is disposed within an opening 11 formed through the rudder 6. The guide bracket 8 allows the rudder 6 to be swung in either direction in a horizontal plane but prevents the same from being swung in a vertical plane. At the rear end of the body-plane 1, are secured a pair of arms 12, connected with the frame-work of the body portion, as shown at 13. These arms 12 carry apertured heads 14, near which are disposed knuckles 15, having suitable opening formed therethrough for receiving a pin 16. The knuckles 15 are suitably connected with the rear rudder 7, whereby the same is hinged to the body-plane 1 and is free to oscillate in a horizontal plane only. A guide bracket 17 has suitable connection with the frame work 2, as shown at 18. This guide bracket extends rearwardly of the body-plane 1 and has the transverse portion thereof disposed within an opening 19 formed through the rudder 7. The rear rudder 7 is connected with the gas-bag 4 by means of a cable 20 which prevents any tendency which the rudder might have to oscillate in a vertical plane, but not interfering with the movement of the same in its horizontal plane.

Means are provided for simultaneously moving the forward and rear rudders 6 and 7 in opposite directions, to cause the machine to change from its line of flight. Such means comprises a pair of cables 21, which are connected with the rudders 6 and 7, as shown at 22 and 23 respectively. The pin 16 which is adjacent the rear rudder 7 carries a transverse rod 24, which is rigidly secured to the same in any suitable manner. This transverse rod is provided at its free ends with pulleys 25 about which are trained the pairs of cables 21. The forward portion of each of the cables 21 is trained about a pulley 26, having suitable connection with the frame-work 2. A lever 27 is employed, the same having suitable connection with a drum or spool 28, about which one of the cables 21 is wound. By the

proper oscillation of this lever the cable 21 may be moved longitudinally to effect the simultaneous movement of the pair of rudders 6 and 7 as above stated. The drum 26, 5 has suitable connection with a platform 28, which is disposed below and suspended from the body-plane 1, as clearly illustrated in Figs. 1 and 2. The platform 28 is suspended by means of shafts 29 and is 10 equipped with pairs of wheels 30 and 31, which are connected to the same by means of brackets 32.

Any suitable means (not shown) may be employed to steer the front wheels 30, preferably such means as are employed upon automobiles for a corresponding purpose. The platform 28 has disposed thereon, and preferably near its center, any well known or preferred type of explosive engine 33, which 20 is adapted to operate transverse horizontally disposed shafts 34. These shafts carry at their outer ends bevel gears 35, which engage bevel gears 36 rigidly mounted upon vertical shafts 37. The pair of vertical 25 shafts 37 carry propellers 38. Attention is called to the fact that the propellers 38 are operated in opposite directions which is caused by one of the bevel gears 36 being positioned above bevel gear 35 while the 30 other bevel gear 36 is disposed below the other bevel gear 35, as clearly illustrated. The function of the propellers 38 is to raise or lower the machine, depending of course, upon the direction of rotation of such propellers. A pair of shafts 39 are disposed 35 above and longitudinally of the platform 28, such shafts carrying upon their inner ends bevel gears 40, which are driven by bevel gears 41 carried by the transverse 40 shafts 34. The shafts 39 carry at their rear ends propellers 42, which rotate in a substantially vertical plane and are preferably driven in opposite directions. The function of the propellers 42 is to effect the travel of 45 the machine in a horizontal plane. The platform 28 is designed to support the operator, who has the engine 33 and other controlling parts of the machine under his supervision.

50 Means are provided to prevent the machine from tilting laterally and to raise and lower the forward end or nose of the same. Such means comprise side wings or planes 43. Each of these side wings or planes is 55 formed of a suitable frame-work 44 and two layers of canvas or other suitable material 45, whereby a space is provided therebetween for the storage of gas. These wings or side planes may thus be made lighter 60 than the air. As clearly shown in Fig. 3, the lower section of canvas 45 is preferably retained in position to form a surface having concaved portions 46. The frame-work 44 above referred to comprises strips 47, 65 which are adapted to retain the lower sec-

tion of canvas 45 in its proper position, as shown. Each of the wings or side planes is connected with the body-plane 1 in such a manner that the said side plane or wing may oscillate longitudinally of the body-plane or 70 transversely thereof, or in other words oscillate in directions which are at right angles to each other. As clearly illustrated in Fig. 5, the frame-work 2 is provided upon each side thereof with brackets 48 to which are 75 hinged rods 49 and 50. The rod 50 is rigidly connected with the rod 49, as shown at 51. Pivotedly mounted upon the rod 49 is a pair of arms 52, capable of being swung longitudinally of the body-plane 1. These 80 arms extend below and are suitably connected with the frame-work of the wing or side-plane 43, whereby the latter is capable of being swung longitudinally of the said body plane 1. Each of the wings or side 85 planes 43 is oscillated transversely of the body-plane 1, by means of a cable 53 which is connected with a bracket 53^a attached to rod 49, see Fig. 5, and which is trained about a suitable pulley 54 secured to the gas- 90 bag above said wing. This cable 53 is endless and extends below the wing 43 to be wound about a drum 55. This drum is suitably mounted upon the platform 28 and may be held fast and suitably rotated by a 95 lever 55^a. The rear end of the wing 43 is oscillated by means of an endless cable 56 which is trained about a pulley 57 above said wing, and wound about a drum 57^a suitably mounted upon the platform, and preferably 100 adjacent the first named drum. Suitable means are to be provided to hold the drum against rotation and then rotate the same to oscillate the wing longitudinally of the body-plane, as shown at 58^a, whereby the 105 nose of the machine is lowered or raised. The exhaust from the explosive engine is conducted by a pipe 58 to the gas-bag 4.

In the operation of the flying machine, the same is propelled forwardly in a horizontal plane by the propellers 42. The operator may guide the machine from its straight line of flight by swinging the forward and rear rudders 6 and 7 in opposite 110 directions, as above described. When the side planes or wings 43 are in their normal horizontal position, for serving as a gliding structure, if the propellers 38 are being rotated to raise the machine, the wings 43 may be tilted downwardly transversely of the body-frame 2, whereby the same will offer the least resistance to the upward movement of the machine. When the propellers 38 are being rotated to cause the machine to descend, the wings 43 may be oscillated upwardly transversely of the body-plane 1 in a similar manner. When it is desired to tilt the machine longitudinally, that is to cause the forward end or nose to rise, the wings 43 115 are swung upwardly longitudinally of the 120

body-plane 1. When the wings are swung downwardly longitudinally of the body plane 1, the nose of the machine will be lowered. Attention is called to the fact that 5 the wings or side planes 43 may be oscillated in two directions which are to be substantially at right angles to each other.

I wish it understood that the form of my 10 invention herewith shown and described is to be taken as a preferred example of the same and that certain changes in the shape, size and arrangement of parts may be resorted to without departing from the spirit of the invention or the scope of the subjoined claim.

Having thus fully described my invention, I claim:—

In a flying machine of the character described, a relatively long supporting plane, 20 a gas bag strapped to the upper surface of the supporting plane, frames hinged upon opposite sides of the supporting plane approximately midway the ends thereof to be swung vertically in a direction transversely 25 of the supporting plane, means including cables for swinging said frames and holding them against movement, relatively small in-

tegral wings pivoted to the frame to be vertically swung so that their angle of incidence may be varied, means including cables 30 to swing said wings and hold them against movement, a supporting structure depending from the supporting plane, means mounted thereon having connection with said cables, oppositely rotating elevation 35 propellers mounted on the supporting structure upon opposite sides thereof, oppositely rotating direction propellers mounted upon the rear end of the supporting structure, common means to drive all the propellers, a 40 rear direction rudder pivoted to the supporting plane, a forward direction rudder pivoted to the supporting plane below the same, cables to swing the direction rudders simultaneously, and operating means mounted upon the supporting structure to move the last named cables.

In testimony whereof I affix my signature in presence of two witnesses.

MARION L. SHACKLEFORD.
